UNITED STATES PATENT OFFICE.

ALBERT L. RUNDELL, OF PROVIDENCE, RHODE ISLAND, ASSIGNOR OF ONE-HALF TO EARL G. DAVIS, OF PLAINFIELD, CONNECTICUT.

ASH-SIFTER.

SPECIFICATION forming part of Letters Patent No. 708,257, dated September 2, 1902.

Application filed October 28, 1901. Serial No. 80,334. (No model.)

To all whom it may concern:

Be it known that I, ALBERT L. RUNDELL, a citizen of the United States, residing at the city of Providence, in the county of Providence and State of Rhode Island, have invented certain new and useful Improvements in Ash-Sifters, of which the following is a specification.

The object of my invention is to provide an ash-sifter arranged to automatically separate the ashes from the cinders.

The invention consists of a casing inclosing a cuneiform screen upon which the material to be sifted is discharged, with two independent drawers to receive the ashes and cinders, respectively, of such construction and arrangement of parts as hereinafter described, and specifically pointed out in the claim.

In the accompanying sheet of drawings, Figure 1 represents a perspective view of the casing with its cover thrown open as ready to receive the material. Fig. 2 is a longitudinal sectional view of the ash-sifter, showing how the material operates while being sifted. Fig. 3 is a central vertical sectional view of the ash-sifter, taken in line $x-x$ of Fig. 2. Fig. 4 represents a perspective view of the drawer which receives the ashes. Fig. 5 is a similar view of the drawer which receives the cinders.

Similar letters of reference indicate similar parts in the different views of the drawings.

A designates the casing as a whole, of a rectangular form in top plan section and having a flat base or bottom b , from which the four walls $c c$ and $d d$ project, the two opposite longitudinal or side walls $c c$ extending vertically from the said bottom to the top of the casing, and the two opposite lateral or end walls $d d$ extending vertically from the said bottom of the casing to points $e e$, situated in a plane about midway of the height of the casing, and from these points the said walls $d d$ slope inwardly to points $f f$, then outwardly-inclined to the top of the casing in the manner as shown in Fig. 2. This casing is provided with an upwardly-swinging cover g , hinged to the end wall d at a point h . An opening is provided in the vertical portion of the end wall d of the casing for the entering of two drawers, which receive the

ashes and cinders, respectively. A frame comprising three bars $j j' j'$ extends horizontally between the sides $c c$ of the casing in a triangular form, the bar j being situated in a plane centrally of the neck or points $f f$ and the other two bars $j' j'$ having their ends resting on two horizontal strips $i i$, secured to the side walls $c c$, with strips $k k$ inclined between the ends of said bars and secured to the said walls of the casing.

B designates a wire screen that is mounted upon the aforesaid frame of the casing and having its outer edges secured to the bars $j j' j'$ and said strips $k k$, and this screen when in position upon the frame, as described, is cuneiform and having its two sides inclined parallel with the upwardly-sloping walls $e f$ of the casing.

C designates the upper drawer, adapted to receive the ashes, having two opposite vertical side walls $m m$ and two transversely-inclined walls $n n$, inclosing a bottom o , as shown in Figs. 2 and 4. This drawer has an extra transverse wall n' , whose outer surface is vertical and its inner surface inclined parallel with the next inner wall n . The rear transverse wall of the casing A is made to incline opposite from the inclined wall n' of the drawer C and parallel with the rear inclined wall n of the same, as seen at n'' . This drawer rests upon two extra strips $i i$, secured to the side walls of the casing, and when the drawer is inserted the top edges of its inclined walls $n n$ are directly under the edges of the transverse bars $j' j'$ of the screen-frame. The exposed inner surface of the casing is covered by a metallic lining l .

D designates the lower drawer, adapted to receive the cinders, having a bottom p , with projecting vertical side walls $q q$ and vertical end walls $r r$, and this drawer is made somewhat longer than the aforesaid ash-drawer for the purpose of bringing the rear wall r beyond the inwardly-inclined portion n'' of the casing. Each of the aforesaid drawers is provided with a metallic lining, as that of the casing. From this description it will be readily understood that when the material to be sifted is placed within the opening at the top of the casing the material will spread over upon each side of the cuneiform screen, and

as the material falls by gravity the ashes pass through the meshes of the screen and into the box portion of the drawer C, while the cinders roll from the screen through the inwardly-inclined chutes of the said drawer, from which they are delivered to the bottom drawer D in the manner as illustrated in Fig. 2.

In the construction of the ash-sifter as described the casing and drawer may, instead of being of wood, be of galvanized iron without departing from the spirit of my invention. This ash-sifter is adapted for family use and forms a simple durable construction and at the same time comparatively inexpensive to manufacture.

Having described my improvement, what I claim, and desire to secure by Letters Patent, is—

In an ash-sifter, the combination, with a 20 casing the upper portion of which has inclined end walls, of a cuneiform screen the sides of which are parallel with but separate from the inclined walls of the casing, an ash-drawer beneath the screen, said drawer having a 25 chute in its forward end and an ash-compartment in rear of said chute, and a cinder-drawer beneath the ash-drawer, said cinder-drawer being of such length as to underlie the chute and extend beyond the ash-compartment, substantially as described.

In testimony whereof I affix my signature in presence of two witnesses.

ALBERT L. RUNDELL.
